United States Patent Office

Des. 201,758
Patented July 27, 1965

201,758

POWER UNIT FOR A FOOD MIXER OR THE LIKE

Robert O. Ernest, Oak Park, Ill., and Richard E. Watson,
Detroit, Mich., assignors to Sunbeam Corporation, Chi-
cago, Ill., a corporation of Illinois

Filed Jan. 13, 1965, Ser. No. 83,416

Term of patent 14 years

(Cl. D44—1)

FIG. 1.

FIG. 2.

6. →

FIG. 3.

FIG. 1 is a perspective view of a power unit for a food mixer or the like, showing the design;

FIG. 2 is an enlarged front view of the power unit for a food mixer or the like;

FIG. 3 is a top view thereof;

FIG. 4 is a side view thereof;

FIG. 5 is a rear view thereof;

FIG. 6 is an enlarged sectional view taken on the section line 6-6 of FIG. 2; and

FIG. 7 is an enlarged sectional view taken on the section line 7-7 of FIG. 5.

The dominant features of the design reside in those portions shown in solid lines.

We claim:

The ornamental design for a power unit for a food mixer or the like, as shown and described.
